UNITED STATES PATENT OFFICE.

EDWIN WALKER, OF ERIE, PENNSYLVANIA.

DESIGN FOR A CIGAR-CUTTER FRAME.

SPECIFICATION forming part of Design No. 25,209, dated March 3, 1896.

Application filed January 11, 1896. Serial No. 575,182. Term of patent 14 years.

To all whom it may concern:

Be it known that I, EDWIN WALKER, a citizen of the United States, residing at the city of Erie, in the county of Erie and State of Pennsylvania, have invented and produced a new and original Design for Cigar-Cutter Frames; and I do hereby declare the following to be a full, clear, and exact description of the invention, such as will enable others skilled in the art to which it appertains to make and use the same, reference being had to the accompanying drawing, and to the letters of reference marked thereon, forming part of this specification.

The figure is a perspective view of my design for a cigar-cutter frame, the leading feature of which consists in a circular case supported upon an ornamental standard mounted upon an ornamental base.

In the accompanying drawing, illustrating my design, A is the base, of substantially oblong shape, the edge A' of which is provided with panels *a a* at the sides, adapted to receive letters forming words, the remainder of the edge being ornamented with scrollwork *a'* in bas-relief. The plain surface of the top of the base A is also adapted to have letters

forming words engraved thereon. Secured centrally upon this base A is a standard B provided with an oblong foot B', the standard and foot thereof being ornamented with scroll-work-figures *b* in bas-relief. Upon the top of the standard B is secured a circular case C, having openings *c c* in the top of the periphery thereof, adapted to receive the points of 30 cigars to be cut. There are also oblong openings *C'* in the sides of the periphery thereof for the operating-levers of the cigar-cutter. The sides of the case are provided with central circular panels D, adapted to receive suitable pictures D'. Curved panels *d d'* are also provided in the frame surrounding the picture D', above and below the same, adapted to receive letters forming words. 35

Having thus described my design, what I 40 claim is—

The design for a cigar-cutter frame substantially as herein shown and described.

In testimony whereof I affix my signature in presence of two witnesses.

EDWIN WALKER.
